UNITED STATES PATENT OFFICE.

WILLIAM L. TETER, OF PHILADELPHIA, PENNSYLVANIA.

TOY HOOP-STICK.

SPECIFICATION forming part of Letters Patent No. 257,785, dated May 9, 1882.

Application filed March 20, 1882. (No model.)

To all whom it may concern:

Be it known that I, WILLIAM L. TETER, of the city and county of Philadelphia, and State of Pennsylvania, have invented an Improvement in Toy Hoop-Sticks, of which the following is a specification.

My invention has reference to hoop-sticks; and it consists in providing the stick on the end with a bell, so that when the hoop is struck 10 the bell will ring; further, in minor details of construction, all of which are fully set out in the following specification and shown in the accompanying drawings, which form part thereof.

15 The object of this invention is to make a hoop-stick as an article of manufacture which shall ring upon handling the same, and thereby please the child who is using it.

In the drawings, Figure 1 is a sectional elevation of my improved hoop-stick, and Fig. 2 is a section view of the bell end of such a stick with a modified form of construction.

A is the stick proper, and is preferably made of wood.

25 D is a metal ferrule which surrounds the end of the stick A to prevent its splitting.

B is a bell which incloses the ball-hammer, as usual, and is secured to the stick by a screw, C, which screws into the end of the stick A, 30 inclosed by the ferrule D. In Fig. 1 this screw

C is shown cast solid with the bell B; but in Fig. 2 it is shown as an ordinary screw with a small head, F, and the bell is provided with a hole, G, in its bottom for the shank of the screw C, and at the top with a hole, E, large enough for the screw-head F to pass through, and through which the screw-driver is inserted.

In this application I do not claim broadly the construction of the bells, as that will form subject-matter of a future application.

Having now described my invention, what I claim as new, and desire to secure by Letters Patent, is—

1. As a new article of manufacture, a toy hoop-stick consisting of the body of wood surrounded on its end with a metallic ferrule, and provided with a globe-bell on said end, substantially as and for the purpose specified.

2. A globe-bell provided on the top with a hole large enough to admit a screw-head and on the bottom with a hole large enough to admit the shank of a screw, in combination with the screw and hoop-stick, substantially as shown.

In testimony of which invention I hereunto set my hand.

WILLIAM L. TETER.
